Moriarty. McNett & Henry LLP(57) CLAIM

The ornamental design for a weight, as shown and described.

DESCRIPTION

FIG. 1 is a perspective view of a weight showing our new design, wherein the broken line showing portions of FIG. 1 are for illustrative purposes only and form no part of the claimed design.

FIG. 2 is a view in front elevation of the weight shown in FIG. 1, the opposite side being a mirror image.

FIG. 3 is a sectional view taken along the line 3—3 of FIG. 2; and,

FIG. 4 is an end-on view thereof.

The weight is encircled by an annular band of a resilient material of a color different from the body of the weight.
